UNITED STATES PATENT OFFICE

2,468,057

MULTIOFFICE TELEPHONE SYSTEM

Fernand P. Gohorel, Antony, France, assignor to
 International Standard Electric Corporation,
 New York, N. Y., a corporation of Delaware

Application October 23, 1943, Serial No. 507,470
 In France February 24, 1939

Section 1, Public Law 690, August 8, 1946
 Patent expires February 24, 1959

2 Claims. (Cl. 179—27)

1

This invention relates to new and useful improvements in multi-office telephone systems in which the operator at the outgoing exchange controls the establishment of connections without the intervention of the incoming or a tandem operator.

The objects of the present invention are to provide certain modifications of the system shown in my Patent No. 2,431,321, issued November 25, 1947, in order to obtain more certain operation of the register, and to permit the reception of the dialling impulses in the form of trains of impulses instead of spaces or interruptions in the dialling current.

In accordance with the invention, in the case in which the impulses are transmitted in the form of trains of impulses, the release of the register and of the detector at the end of the reception of the impulses, is effected without counting the number of trains of impulses received. For this purpose an impulse is sent from the outgoing exchange at the end of dialling when, for example, the operator releases her dial key of the cord pair. This impulse causes at the incoming exchange, the release of the register and of the detector.

The various characteristic features of the invention will more clearly appear from the following description with reference to two embodiments diagrammatically illustrated in Figs. 1 and 2, which show as much as is necessary for understanding the invention and which are given by way of non-limiting examples.

First, the operation of a modified register in Fig. 1 will be explained, this register being provided to receive the impulses transmitted in the form of spaces in a dialling current. In this connection attention is directed to the above-mentioned co-pending application.

When earth is applied to starting wire 52, relay 28 is energized on its lower winding. At the end of the testing of the detector associated with the register, earth is applied to wire 23' which operates relay 30 on its lower winding. The automatic stepping circuit of finder C₀₃ is completed. The wipers of this switch hunt for the incoming equipment on which the call has been received. When this equipment has been found, the circuit of relay 29 is completed and this relay pulls up and stops the wipers of C₀₃ by opening the circuit of magnet C_{m3}. The circuit of the upper winding of relay 30 being now completed, this relay falls back. The circuit of relay 32 is completed.

When relay 32 pulls up, the register and the

detector equipment are connected to the incoming equipment.

After the free equipment of the automatic switch has been connected to the incoming equipment, relay 40 pulls up.

When the dialling current transmitted by the outgoing exchange is received at the incoming exchange, relay 36 pulls up and completes at T362 the circuit of relay 2, which pulls up after a moment.

As disclosed in the co-pending application, upon each disconnection of the dialling current relay 34 is energized, and through T342 and T22 completes the circuit of relay 38 which pulls up.

15 At the end of the disconnection of the voice frequency current corresponding to one impulse, relay 34 falls back. Relay 38 is held and the upper winding of relay 37 is energized to complete the circuit of magnet C_{m1}.

20 The magnet C_{m1} advances wipers C₀₁ by one step causing the release of relay 38 which short-circuits the lower winding of relay 37. This relay is sufficiently slow to remain up while a train of impulses is transmitted.

25 The wipers C₀₁ of C_{m1} thus advance one step upon each impulse received.

At the end of the reception of the train of impulses, relay 37 and relay 36 are de-energized, and the charging of the condenser connected 30 to the bank of C₀₁ will take place. The various trains of impulses are registered.

The manner in which the re-transmission of the impulses takes place will now be explained.

When relay 35 pulls up, it completes the following circuit for relay 5: battery, winding of 5, R441, R392, T401, T352, T321' and earth. After a moment relay 5 pulls up and at T51 completes the energizing circuit of relay 42. Relay 42 pulls up after a brief delay and completes at T423 the following circuit of relay 41: battery, winding of 41, T423, R52 and earth. After a moment relay 41 pulls up, and relay 43 is energized to complete through T431 the control circuit of magnet C_{m2} of switch C₀₂. Through T432, it completes the 45 impulse repeating circuit.

The repetition of the impulses and the advance of the switches C₀₁ and C₀₂ take place now.

When relay 42 falls back it opens at T423 the circuit of relay 41 and at T422 it removes the short-circuit from relay 5. Relay 41 having returned to normal, completes the impulse circuit and relay 40 being energized, opens at 401 the circuit of relays 43, 44 and 45, which fall back.

As soon as relay 44 falls back, the circuit of 55 relay 5 is again completed, whereupon a fresh

train of impulses is retransmitted, as above described.

At the end of the dialling, the restoration of the register to normal takes place.

Fig. 2 shows a register similar to that of Fig. 1, but which has been adapted by very simple modification to receive dialling impulses in the form of trains of impulses.

The impulse relay 34 is no longer connected to wire 26' of the detector, but to wire 25' which is disconnected from relay 36. When relay 32 is energized, the following holding circuit for relay 36 is completed: battery, R354, T326, winding of 10 36 and earth.

The impulses are received upon each pulling-up of the impulse relay of the detector (relay 53 of Fig. 5 of the patent above referred to). Relay 34 pulls up whereupon the register operates as previously described.

When the termination of the dialling impulse is signalled to the outgoing exchange, for example, when the operator releases her dial key, the detector causes the pulling up of relay 34 followed by the pulling up of relays 38, 37 and 35.

The end-of-dialling impulse is long enough to open the circuit at R354, so as to cause the de-energization of the slow-acting relay 36 which is not released during the opening of R354 upon the reception of the dialling impulses.

The other operations in the register are the same as in the previous case.

What is claimed is:

1. In a telephone system, a plurality of exchanges, lines terminating at said exchanges, trunk lines interconnecting said exchanges, operators' positions at said exchanges, an impulse device at the calling exchange operator's position operable in accordance with the numerical designation of a called line, a source of voice fre-

quency current at the calling exchange from which trains of current impulses are sent over a trunk line to the called exchange under the control of the impulse device, a register controller at the called exchange variably operable by said impulse device, automatic selector switches at the called exchange adapted to select a called line and operable under the control of said register controller, means at the called exchange for connecting said register controller with the trunk line through which the calling exchange is connected with the called exchange, and means at the calling exchange for sending an impulse towards the called exchange upon the termination of the operation of said impulse device for releasing said register controller.

2. The telephone system according to claim 1, and a key at the calling exchange operator's position for connecting, when operated, the impulse device with a trunk line, said key constituting the last-mentioned means, being adapted upon its release to send the register releasing impulse towards the called exchange.

FERNAND P. GOHOREL.
